[57] CLAIM

The ornamental design for a wrist band, as shown and described.

DESCRIPTION

FIG. 1 is an enlarged scale perspective view of a wrist band in use and showing my new design;

FIG. 2 is a top view thereof;

FIG. 3 is a right side elevational view thereof;

FIG. 4 is a left side elevational view thereof;

FIG. 5 is a bottom view thereof;

FIG. 6 is a front elevational view thereof; and,

FIG. 7 is a rear elevational view thereof.

The dashed lines in FIG. 1, 2, and 5 represent conventional stitching.

The broken line showing of an arm on which the wrist band is worn in FIG. 1 is for illustrative purposes only and forms no part of the claimed design.
